UNITED STATES PATENT OFFICE.

ASHER B. STEVENS, OF NEW BRIDGE, NEW JERSEY, ASSIGNOR, BY
MESNE ASSIGNMENTS, TO THE ROCKER SPRING COMPANY, OF
CHICAGO, ILLINOIS.

SPRING ATTACHMENT FOR ROCKING-CHAIRS.

SPECIFICATION forming part of Letters Patent No. 374,854, dated December 13, 1887.

Original application filed October 8, 1883. Serial No. 108,413. Divided and this application filed January 28, 1886. Serial No. 190,081. (No model.)

To all whom it may concern:

Be it known that I, ASHER B. STEVENS, a citizen of the United States, residing at New Bridge, in the county of Bergen and State of New Jersey, have invented a certain new and useful Improvement in Spring Attachments for Rocking-Chairs, of which the following is a full, clear, and exact description.

The object of my invention is to make an attachment for rocking-chair springs that will hold the ends of the spring rigidly when in place, and at the same time enable the spring to be removed and the chair shipped in separate pieces without disturbing or removing the portions of the brackets which are screwed to the rockers or base-rails; and it consists in the features of construction and arrangement hereinafter described.

In order to differentiate between the invention herein claimed and the separable or two-part brackets covered in my applications, Serial Nos. 190,083 and 190,084, filed January 28, 1886, I here state that the invention herein consists, broadly, of the bracket made in two parts, one attached to the coiled spring and the other adapted to be attached to the appropriate portions of the chair, the two when in operation being secured or fastened together.

In the accompanying drawings, in the two figures of which like parts are similarly designated, Figure 1 is a top plan view, and Fig. 2 is a cross-section, in the plane of line y y of Fig. 1, of one form of my invention.

This division of my application Serial No. 108,413 is made for the purpose of covering the two-part bracket therein shown and described.

The bracket B is composed of a base, a , provided, as usual, with holes for the passage of fastening devices—as screws—to secure the same to a chair, and an arm, b . This portion of the bracket when once upon the chair may

remain there. The spring is screwed or slipped or snapped upon the removable portion b' of the bracket, as in the case referred to, and this portion b' has lugs h h , adapted to receive the arm b , the two being secured by a screw, s , which permits their ready attachment and detachment for purposes of use and transportation. The portion b' of the bracket has its rim provided, as shown, with projections which engage the spring between and by its end coils. The portion b' , when once applied to a spring, may remain with it, and when the spring is to be disconnected from the bracket the screw s is withdrawn, and the portion b' with the spring is free to be removed.

What I claim is—

1. The combination of the bracket-base, spring-attaching portion b' , arm b , projecting laterally from the base and engaging the spring-attaching portion, and means for locking the parts b and b' together, substantially as described.

2. The combination of the bracket-base a , spring-attaching portion b' , adapted to receive the end coil of a spiral spring, arm b , projecting laterally from the base and engaging the spring-attaching portion, and a screw or bolt, s , for fastening the parts b and b' together, substantially as described.

3. The combination of the base a , laterally-projecting arm b , an attachable portion, b' , adapted to receive the end coils of a coiled spring and having lugs h h arranged upon its upper surface to engage the sides of the arm, and a fastening device, s , substantially as described.

In testimony whereof I have hereunto set my hand this 27th day of January, A. D. 1886.

ASHER B. STEVENS.
